[57] **CLAIM**

The ornamental design for a front bezel for a desktop computer, as shown and described.

DESCRIPTION

FIG. 1 is a right front perspective of a front bezel for a desktop computer incorporating the new design;

FIG. 2 is a left side elevation thereof; and

FIG. 3 is a bottom plan view thereof.

The desktop computer is shown in broken lines in the views for illustrative purposes only and forms no part of the claimed design.
